(57) **CLAIM**

The ornamental design for a base unit for displaying one or more balloons, as shown and described.

DESCRIPTION

FIG. 1 is a top perspective view of a base unit for displaying one or more balloons showing our new design;

FIG. 2 is a front elevational view, the rear elevational view being a mirror image thereof;

FIG. 3 is a right side elevational view, the left side elevational view being a mirror image thereof;

FIG. 4 is a top plan view thereof; and,

FIG. 5 is a bottom plan view thereof.

The broken line periphery in FIG. 1 represents a boundary, the area within which forms no part of the claimed design.
